DESIGN FOR A CHRISTMAS TREE LIGHT HOLDER

Henry Haase, Detroit, Mich.

Application February 25, 1936, Serial No. 61,337

Term of patent 3½ years

To all whom it may concern:

Be it known that I, Henry Haase, a citizen of the United States, residing at Detroit, in the county of Wayne and State of Michigan, have invented a new, original, and ornamental Design for a Christmas Tree Light Holder, of which the following is a specification, reference being had to the accompanying drawing, forming part thereof.

Figure 1 is a top plan view of a Christmas tree light holder, showing my new design.

Figure 2 is a view in side elevation thereof.

Figure 3 is an end elevational view.

I claim:—

The ornamental design for a Christmas tree light holder, as shown.

HENRY HAASE.
